(Cl. D7—7)

Fig. 1

Fig. 2

Fig. 1 is a front perspective view of a shoe or similar article showing my new design.

Fig. 2 is a fragmentary view of the shoe shown in Fig. 1 illustrating its appearance when on the foot.

The dominant feature of my design resides in the portions shown in solid lines.

I claim:

The ornamental design for a shoe or similar article, substantially as shown and described.
